United States Patent Office

Des. 184,463
Patented Feb. 17, 1959

184,463

WALL BLOCK

Edward D. Stone, New York, N. Y.

Application September 18, 1957, Serial No. 47,772

Term of patent 14 years

(Cl. D18—2)

Fig. 1 is a front elevation of a wall block showing my new design;

Fig. 2 is a side elevation of the wall block;

Fig. 3 is a bottom view of the wall block; and

Fig. 4 is a perspective view of the wall block.

I claim:

The ornamental design for a wall block, substantially as shown.
